L. F. DAVIS

SUCKER ROD ELEVATOR

Filed Sept. 3, 1925

FIG. 1.

FIG. 2.

FIG. 3.

INVENTOR,
Lewis F. Davis.
By Martin P. Smith Atty.

UNITED STATES PATENT OFFICE.

LEWIS F. DAVIS, OF SANTA ANA, CALIFORNIA.

SUCKER-ROD ELEVATOR.

Application filed September 3, 1925. Serial No. 54,170.

To all whom it may concern:

Be it known that I, LEWIS F. DAVIS, a citizen of the United States, residing at Santa Ana, in the county of Orange and State of California, have invented certain new and useful Improvements in Sucker-Rod Elevators, of which the following is a specification.

My invention relates to an oil well appliance known as a sucker rod elevator and which is used in the handling or manipulation of the pump or sucker rods while the same are being withdrawn from a well or lowered thereinto, the principal objects of my invention being to generally improve upon and simplify the construction of the existing forms of similar devices and to provide an elevator that may be easily and cheaply produced and which is practically automatic in its engagement with a sucker or pump rod.

Further objects of my invention are to provide an elevator of the character referred to that has comparatively few operating parts thereby minimizing the liability of the elevator becoming inoperative due to disarrangement of parts, to provide an elevator wherein the locking or latching member is pivoted to the elevator housing with relation to the pivotal point rod engaging member so as to provide a toggle arrangement that will effectually resist all tendencies of the engaged rod to move forwardly out of the rod receiving slot or opening in the housing, and further to construct the upper portion of the elevator block or housing so that the weight of the engaged sucker rod will normally tend to force said rod to the rear end of the slot or opening in the housing and consequently counteract any tendencies of said rod to move forwardly out of said slot.

A further object of my invention is to provide a sucker rod elevator with a lock or latching member that may be very readily engaged and shifted into position to release the rod engaging member and further to provide an elevator that is of strong, rugged and substantial structure so as to be capable of withstanding the rough usage to which devices of this character are subjected while in service.

With the foregoing and other objects in view, my invention consists in certain novel features of construction and arrangement of parts that will hereinafter be more fully

described and claimed and illustrated in the accompanying drawing, in which—

Fig. 1. is a perspective view of a sucker rod elevator of my improved construction. 60

Fig. 2. is an enlarged horizontal section taken approximately on the line 2—2 of Fig. 1.

Fig. 3. is an enlarged sectional view taken approximately on the line 3—3 of Fig. 1. 65

Referring by numerals to the accompanying drawing which illustrates a practical embodiment of my invention, 10 designates a metal block that is preferably cast in a single piece and which forms the body of 70 the elevator. This block is made hollow thereby providing a chamber 11 that is open front and rear and formed integral with and projecting outwardly from the sides of the block are trunnions 12 that serve 75 as points of pivotal connection for the lower ends of the legs of a bail 13.

Formed in the block and extending inwardly from its front end to a point adjacent to the center of said block is a slot or opening 14 which is for the reception of the well or sucker rod. The rear end of that portion of this slot 14 that is formed in the wall of the block above the opening 11 is formed slightly larger in diameter than are the 80 sucker rods that are engaged by the elevator, and formed on the upper surface of the body of the block immediately in front of this enlarged rear end of the slot are upwardly projecting lugs 15 having inclined rear or inner shoulders 16. These shoulders are adapted to bear against the curved or inclined shoulders that are formed on the sucker rods adjacent to the joints thereof and as a result of such engagement the 85 weight of the engaged sucker rod causes the same to gravitate toward the rear end of slot 14 and consequently counteract any 90 tendency of the engaged sucker rod to move forwardly through the slot or for the elevator to move rearwardly away from the 95 rod.

The outer end of rod receiving slot 14 is gradually widened so as to readily receive the rods when the elevator is applied 100 thereto.

The outer end of a short rod engaging member or dog 17 is pivotally mounted on a pin or rivet 18 that passes through the upper and lower walls of the hollow block 110 10 and said pin or rivet being located near one side of the block and in approximately

2

transverse alignment with the rear end of the rod receiving slot or opening 14. The inner or free end of this dog is bifurcated or made substantially U-shaped to provide a relatively short front arm 19 and a slightly longer rear arm 20. These arms are spaced apart to form a substantially U-shaped opening 21 that is adapted to coincide with the rear end of the rod-receiving slot 14 when a rod is engaged by the elevator. The outer end of the shorter arm is provided with an inclined face or shoulder 22 and the outer end of the longer arm 20 is provided with a correspondingly inclined face or shoulder 23. 10 Seated in the forward portion of the block 10 immediately adjacent the mouth or opening into slot 14 is a pin or rivet 24 and pivotally mounted thereupon is the forward end of a dog-latching or locking member 25. This latching member extends in a general direction rearwardly through the central portion of the chamber 11 in the block and interposed between the said portion of said latching member and the adjacent side wall of block 10 is an expansive coil spring 26 that tends to force said latching member toward the rod-receiving slot 14 and the dog 17. 20 The lines that intersect pivot pins 18 and 24 and the center of the rod-receiving opening at the rear end of slot 14 form an obtuse angle, thereby producing a toggle arrangement between the dog 17 and latch member 25, when a rod is locked in the elevator, and the parts occupy the positions as illustrated in Fig. 2.

The intermediate portion of latching member 25 and which occupies a position to the side of the rear end of slot 14 is bent outwardly as designated by 27 for the accommodation of the free ends of the arms 19 and 20 and the rear end of said latching member terminates in a thumb or finger plate 28 that normally occupies a position in the rear central portion of opening 11. 40

Formed on the inner face of member 25 directly in front of the bent intermediate portion 27, is a shoulder 29, that is adapted to engage the inclined face or shoulder 22 to lock the dog 17 in rod-engaging position. 50

Formed immediately adjacent to this shoulder 29 is a lug 30, behind which engages the end of longer arm 20 when dog 17 is in open position or position to receive a rod as it passes into the slot 14, and when the dog is thus positioned, inclined face 23 rests on shoulder 29. 55

Dotted lines in Fig. 2 show the relative positions of parts 17 and 25 when in position to receive a sucker rod. 60

When a sucker rod is engaged by the elevator and locked therein the under surface of the inclined or tapered shoulder on the engaged rod rests on the inclined shoulder 16 of lugs 15 as illustrated in Fig. 3 and the

weight of the engaged rod tends to cause the same to move inwardly to the rear end of the slot 14 and retain such position. The engaged rod occupies the U-shaped opening 21 between the arms 19 and 20 of dog 17 and latching member 25 under the influence of spring 26 occupies the position as illustrated by solid lines in Fig. 2 with shoulder 29 in engagement with shoulder 22 on arm 19. 70

Thus the rod engaging dog is very securely held and locked in rod engaging position and this locking effect is enhanced by the relative angular arrangements of the pivot pins 18 and 24 with respect to the axis of the engaged rod, for, as heretofore stated, such an arrangement is in effect a toggle, that cannot be "broken" or released by forward stresses or strains imparted by the engaged rod. 75

To release dog 17 and permit the parts to move into position to release the engaged rod, thumb plate 28 is engaged and moved in the direction indicated by the arrow in Fig. 2 and thus shoulder 29 is moved away from shoulder 22, thus freeing dog 17 and as the rod is moved forward through slot 14 or as the elevator is moved away from the rod, said dog will swing into the position shown by dotted lines in Fig. 2 with inclined face 23 in engagement with inclined face 29 behind lug 30 and thus the force exerted by spring 26 is utilized to hold (or cock) the dog 17 in its open position with arm 20 in position to be engaged by a sucker rod when the latter is moved into slot 14. 90

Thus it will be seen that I have provided a sucker rod elevator that is relatively simple in construction, comprising but three main parts and a spring, and which elevator may be easily and cheaply produced and which is very effective in performing its intended functions. 105

The bearing of the engaged rod against shoulder 16 prevents undue strains developed by the rod from being impressed on the dog 17 and the latter is very firmly retained in its rod engaging position by latch member 25 and the toggle-like arrangement between said member and dog. 110

It is to be understood that the form of the invention herein shown and described is to be taken as a preferred example of the same and that various modifications in the shape, size and arrangement of parts may be resorted to without departing from the spirit of the invention or the scope of the subjoined claims. 115

I claim as my invention:

1. In a rod elevator, a block provided with a chamber and with a rod-receiving slot extending inwardly from its front face, a rod-engaging dog arranged within the chamber in said block and pivotally mounted therein to one side of the rod-receiving slot and a 120

spring pressed dog latching member arranged within the chamber and its forward end being pivotally connected to said block to one side of the open front end of the rod-receiving slot.

2. In a rod elevator, a hollow block having a rod-receiving slot extending inwardly from its front face, a dog pivoted within said hollow block and having arms that are adapted to engage a rod positioned at the rear end of the slot in said block and a spring held dog latching member pivotally connected to the front portion of said block adjacent to the side of the outer end of said rod-receiving slot.

3. In a rod elevator, a block provided with a rod-receiving slot extending inwardly from its front face and rearwardly inclined rod-bearing shoulders formed on top of said block to the sides of the slot therein immediately in front of the rear end of said slot.

4. In a rod elevator, a block provided with

a rod-receiving slot extending inwardly from its front face, rearwardly inclined rod-bearing shoulders formed on top of said block to the sides of the slot therein immediately in front of the rear end of said slot and means within the block for locking the rod that occupies said slot and rests upon said shoulders.

5. In a rod elevator, a block provided with a rod-receiving slot that extends inwardly from its front face and rod-engaging shoulders formed on top of said block for normally forcing an engaged rod toward the rear of said slot.

6. In a rod elevator, a block provided with a rod-receiving slot that extends inwardly from its front face, rod-engaging shoulders formed on top of said block for normally forcing an engaged rod toward the rear of said slot and means within said block for locking the engaged rod.

In testimony whereof I affix my signature.
LEWIS F. DAVIS.
